UNITED STATES PATENT OFFICE.

CHARLES ADIS PURVIS, OF MOUND CITY, KANSAS, ASSIGNOR TO THE PURVIS MANUFACTURING COMPANY, OF MOUND CITY, KANSAS, A CORPORATION OF KANSAS.

DOOR OPENING AND CLOSING DEVICE.

Application filed February 23, 1926. Serial No. 89,847.

This invention relates to double-door operating mechanism of the general type disclosed in my Patent No. 1,527,077, February 17, 1925, in which provision is made for tripping a fastening mechanism by a pull-cord, to permit of automatic closing of the doors, one of the objects of the present invention being to provide a construction whereby one desiring to effect the closing of the doors, can accomplish such object by pressing a particular door more widely open, and thereby trip the fastening mechanism, performing this operation with his elbow if it happens his hands are both employed in holding articles or packages, as frequently is the case in the placement of articles of merchandise in rear double-door delivery automobiles or horse drawn vehicles.

With this general object in view, and others pertaining to simplicity, efficiency and economy of construction, the invention consists in certain novel and useful features of construction and combinations of parts, as hereinafter described and claimed; and in order that it may be fully understood, reference is to be had to the accompanying drawing, in which:—

Figure 1 is a horizontal section of a construction embodying the invention, taken in the plane of the dotted line I—I of Figure 3, and showing the doors in closed position.

Figure 2 is a similar view, but showing the doors in open position.

Figure 3 is a front view of the construction as disclosed by Figure 2.

Figure 4 is an enlarged section on the dotted line IV—IV of Figure 2.

Figure 5 is a section on the line V—V of Figure 4.

Figure 6 is an enlarged section on the line VI—VI of Figure 1.

Referring to the drawing in detail, 1 indicates the framing for a pair of double-doors 2 and 3, hinged as customary at their outer edges, the door 3 being provided with a handle 4, to be grasped when it is desired to open the doors.

Bolted, as shown, or otherwise rigidly secured to the inner side of door 2 near the hinged edge and upper margin of said door, is a bracket 5, and bolted to said bracket and abutting the door so as to stand as an inwardly-projecting rigid arm thereof, is an angle iron arm 6, provided near its inner or free end with a depending latch tongue 7,

and outward of said tongue a vertical, inverted bolt 8, is threaded in the arm. A brace 9 for said arm, is mounted at one end upon said bolt and at the other end is secured rigidly to door 2, as at 10.

Bolted or otherwise rigidly secured to the inner side of door 3 at a greater distance from the hinged edge of said door than bracket 5 is from the hinged edge of door 2, is a bracket 11, and pivotally connected by a bolt 12 to bracket 11 is an arm, preferably consisting of two angle bars 13 and 14 nested adjustably together and engaged by a pair of angularly-disposed hooks 15 and 16, the shank of hook 16 being of bolt form and extending through the shank of hook 15. A nut 17 engages the shank of hook 16 and by adjustment is utilized to clamp the arms of the angle bars 13 and 14 rigidly together to produce an arm of the required length.

The arm composed of bars 13 and 14, has a short longitudinal slot 18, pivotally receiving the bolt 8 between the head thereof and arm 9, the arm 13—14 having a slight longitudinal play in the opening movement of the doors, on the bolt. At the adjacent extremity of bar 13 there is formed a notch 19, and the said bar has a bevelled edge 20 leading to said notch.

A retractile spring 21 is secured at one end to the opposite end of bracket 11 from the pivot bolt 12, and a link rod 22 connects the other end of said spring with the bolt 8, a nut 23 being engaged with said bolt between the link rod 22 and the brace 9, to hold the latter flatly upon the arm 6.

When the doors are closed the parts stand in the position shown by Figure 1, the spring 21 at such time being under sufficient tension to hold the doors closed. When handle 4 is grasped and an outward pull applied thereon, the tension on the spring is increased and utilizes the leverage of the arm 6 to cause the door 2 to start on its outward swing. As the swinging movement continues, the arm 13—14 by pulling on the bolt 8, takes up the burden of transmitting power from door 3 to door 2 to continue the opening movement of the latter, and as the doors attain full opened position, as shown most clearly by Figure 2, the said arms gradually approach a position of alinement, and as they nearly attain this position the play permitted on the part of the power-transmitting arm 13—14, permits the tongue 7 to ride over

the bevelled end 20, and the pull of the spring, as said tongue registers with notch 19, snaps the former into the latter and thus locks the arms in alinement, it being noted that because said arms are overlapping and of angular type, it will be impossible if the doors are opened with too much force, for the arms to move beyond a longitudinally alined relationship.

19 For relatively small doors, such as found on delivery wagons and the like, wind pressure will not ordinarily be sufficient to overcome the resistance of spring 21 and thus impart right-hand movement to arm 13-14 sufficient to disengage it from the locking tongue 7, and hence no auxiliary spring, such as used in my prior patented construction, is necessary or desirable. When the operator desires to close the doors, however, 20 he can merely apply outward pressure with his elbow on the right-hand door, to swing it enough to effect disengagement between the notch 19 and tongue 7. As the outward pressure on said door 3 is relaxed, the reaction of the spring by applying force at an angle to the alined arms 6 and 13-14, breaks the joint between said arms and effects simultaneous closing movement of both doors.

20 From the above description it will be apparent that I have produced a double-door operating mechanism embodying the features of advantage set forth as desirable in the statement of the objects of the invention, and which is obviously susceptible of modification in minor particulars without departing from the principle of construction involved or sacrificing any of the advantages of the appended claims, it being noted in this connection that not only does the construction lack the pull-cord and auxiliary door-closing spring of the prior patent hereinbefore identified, but it also shows the fastener or latch mechanism transposed, 25 in that the tongue is on the short rigid arm 6 and the notch on the long arm, instead of having the notch in the short arm and a separate latch piece on the long arm, as shown by the aforesaid patent. It will be also understood that the present improvement while peculiarly appropriate for small 30 double-doors, may be employed on inside or outside doors for buildings.

I claim:

55 1. The combination of a pair of doors hinged at their outer edges, a rigid arm projecting inwardly from one of the doors at the hinged edge thereof, an arm extending obliquely from the inner end of the rigid arm toward the hinged edge of the other door and having a pivotal relation with and at the inner side of the latter and having a pivotal and longitudinal play relation

with said rigid arm, tensioned retractile means between the last-named door at a 25 point between its free edge and its point of pivotal relation with said oblique arm, and the inner end of said rigid arm; one of said arms having a beveled end and a notch, and the other arm a tongue adapted during the 70 opening movement of the doors to engage and ride over said beveled end until the two arms are alined, and said retractile means being adapted as the force applied to open the doors is removed, to react and effect 75 engagement between said tongue and notch to fasten the arms alined and the doors against closing movement.

2. The combination with a pair of doors hinged at their outer edges, an arm projecting rigidly inward from one of said doors near the hinged edge thereof, a vertical pivot bolt carried by said arm, an arm fitting flatly against the inner end of the first-named arm and having a longitudinal slot 85 engaging said pivot bolt, and extending therefrom obliquely toward the hinged edge of the other door, a bracket secured to the inner side of the last-named door at a point intermediate its width and pivoted to the 90 adjacent end of the oblique arm, and a retractile means connected at one end to said pivot bolt and extending divergingly toward the other door with respect to said oblique arm, and connected to said bracket 95 between the adjacent end of said oblique arm and the free edge of the last-named door; said rigid arm having a tongue at an intermediate point and the oblique arm a 100 beveled end for the tongue to ride over during the opening movement of the doors, and a notch for the tongue to engage when the force applied to open the doors is relaxed to permit the retractile connection to react 105 and effect the engagement of said tongue and notch to fasten the doors in open position.

3. In a double-door operating mechanism, an arm composed of a pair of angle irons, one nested in the reentrant angle of the 110 other, hooks extending at intersecting angles and fitting flatly against and crosswise of the outer sides of the respective arms of the outer angle iron, the shank of one hook being threaded and extending through the shank of the other hook, the hook terminals fitting over the free edges of the arms of 115 both angle irons and engaging the outer edges of the respective arms of the inner angle irons, and a nut engaging the threaded shank and the outer side of the other shank to cause the hooks to clamp the angle irons firmly together.

In witness whereof I hereunto affix my signature.

CHARLES ADIS PURVIS.
